DISPENSING CONTAINER

Paul D. Peterson, Ligonier, Pa., assignor to The
Koppers Company of Delaware, a corporation
of Delaware

Application April 23, 1932. Serial No. 607,018

6 Claims. (Cl. 43—146)

This invention relates to the art of packaging substances in powdered form. It relates especially to dispensing containers for pulverulent materials, such as fungicides, insecticides, dusting powders and the like.

An object of my present invention is to provide an improved dispensing container from which insecticides and the like may be efficiently discharged in any desired direction without waste.

16 A second object of my invention is to provide a simple and compact container for pulverulent material which also serves as a dispenser or a dust gun of high efficiency.

Another object of my invention is to provide a dispensing container for fungicides, insecticides, and other pulverulent material which is especially adapted to apply such materials to foliage and the like from below.

My invention has for further objects such other advantages and results as are found to obtain in the container hereinafter described and claimed and in the process of manufacturing said container.

A dispensing container of high efficiency is described in my copending application Serial No. 498,023, filed November 25, 1930. That container combines a dust gun or dispenser of the bellows type with a compact and attractive carton of regular shape, thereby forming a dispensing container of high efficiency which is economically manufactured and which is of such shape that it is well adapted for use in the sale or shipment of insecticides and the like.

An improved dispensing container of somewhat similar construction and appearance is described in my copending application Serial No. 572,918, filed November 4, 1931. In some respects the present invention is an improvement on the containers described in the aforementioned applications, the improvements and novel features of the container described hereinbelow making it well adapted for a variety of purposes which required special equipment or which could not be satisfactorily realized with previously existing dusting equipment.

For example, in the control of certain pests, it is desirable to dust rose bushes and the like very thoroughly from below, and to make the dust adhere to the bottom of the leaves a heavy dust cloud of low velocity is needed. No available apparatus would answer this purpose in a satisfactory manner and this condition was one of the factors leading to the development of my improved device which is described herewith.

55 While a dispensing container capable of applying

ing dust in heavy clouds of low velocity to the under side of low-growing foliage is in itself novel and highly useful, and while I may in some instances construct containers for this purpose alone, I prefer to include this feature in a dispensing container of the type described in my copending applications referred to hereinabove, such containers being already well adapted for all other dusting purposes, such as dusting downward without dumping and dusting upward into tall shrubs, vines, etc.

60 My present invention may, therefore, be said to contemplate certain improvements in dust-dispensing containers of the single purpose or all-purpose type and especially a new combination dispensing container adapted to all dusting purposes.

65 In order that the nature of my invention may be more readily understood, I will now describe an improved container constructed in accordance therewith with reference to the accompanying drawings, in which

70 Figure 1 is a perspective view of a container with the bellows partially open;

75 Fig. 2 is a similar view of the container with the bellows closed and sealed;

Fig. 3 is another perspective view, showing the bellows in place and partly closed;

80 Fig. 4 is a similar view of one-half of the container with a non-dumping manifold in place therein;

85 Fig. 5 is a plan view of a blank from which a preferred type of manifold is folded;

Fig. 6 is a view of the partly folded manifold; and

90 Fig. 7 is a perspective view of the completed manifold.

Referring to Fig. 1, my improved container comprises two rectangular box-like sections 1 and 2 which are preferably but not necessarily substantially equal in size. These two sections are brought together along one edge 3 and joined by a suitable hinge of paper, cloth, or the like.

95 On the other three sides, the two side sections are joined by a bellows 5. The side sections may be constructed of cardboard or other suitable relatively rigid material and the bellows may be made of paper with or without reinforcements of cloth or other material, as will be described hereinbelow.

100 When the dispensing container is to be used for an all-purpose duster, as is generally the case, a side section 1 thereof is provided with a discharge port 7 which may be of any desired size and shape and located in any desired part of the

105

110

hinged end of the carton. This port is preferably near a corner of the carton, however, as shown in the drawings, and it preferably communicates with the interior of the carton through a non-dumping manifold, which will be described hereinbelow. Air is drawn in and air and dust are discharged through the port and manifold by the action of the bellows.

Whether or not the discharge port 7 and the manifold communicating therewith are employed, a vertically discharging port 9 is provided in one side of the container. In the preferred instance, when ports 7 and 9 are both provided, the port 9 is in the upper side of the box 10 near the hinged end when the port 7 is in its preferred position in an upper corner of the hinged end, as shown. It is also preferable to have the port 9 in the opposite side section from port 7: that is, when port 7 is in section 1, port 9 is preferably in section 2.

This vertically discharging port 9 makes it possible to apply heavy clouds of dust of low velocity to the under side of low-growing foliage and the like. The port opens directly from the 15 interior of the container and may be located in any side thereof perpendicular to the hinged end, which makes it adapted to discharge dust upwards when the greatest dimension of the container is in a substantially horizontal plane.

The location of port 9 in proximity to port 7, but in the opposite section of the container, in the manner shown, is usually preferable, however, as the container is then adapted to be held and operated in the same manner for any dusting purpose.

As in the case of port 7, the port 9 may be of any desired size and shape, but it is usually convenient to have both ports substantially circular and of substantially the same size, such as 40 from $\frac{1}{2}$ inch to 1 inch in diameter, for example. The most desirable size, of course, depends on the size of the container and the nature of the material to be dispensed thereby. When two ports are provided and both are of substantially the 45 same size, an interchangeable cork or other stoppering device can be employed to close off whichever port is not in use in any dusting operation.

Whether the two ports 7 and 9 are provided, or only one of them, it is sometimes convenient to 50 provide a separate filling port 10, as indicated by dotted lines in the drawings. This filling port may be in either side section of the container and in any desired location but it is usually preferable to locate it in the hinged end of one of the side sections. In most instances, however, the filling port 10 is omitted, as the port 9 is well adapted to serve as a filling port in addition to being a discharge port.

When the container is assembled as shown in 55 Fig. 1, it is ready to be filled for shipment or sale. The bellows is then closed, bringing the two sections of the container into parallel relation as shown in Fig. 2. They are retained in this position by means of a strip or seal of adhesive material 11 of any desired width which extends part or all the way around the container. In the drawings, the strip 11 is shown as equal in width to the thickness of the closed container to which it is applied on three sides.

A rip cord 12 is preferably laid around the 60 dividing line between the two sections prior to application of the seal 11, with one end of the cord extending beyond the seal, as shown in the present instance. Alternatively, the rip cord 75 may be fastened to the seal or wrapping before

the latter is applied to the container, in which case the rip cord and seal are simultaneously applied in a single operation. The rip cord may extend completely around the container or only part way around as, for instance, along one side 80 and across the end opposite the hinge.

In assembling the container, a bellows of strong paper or other suitable material is prepared as described in my copending applications referred to hereinabove. I prefer to employ the 85 improved type of bellows described in my application No. 572,918. Such a bellows is prepared from a polygonal blank consisting of an end section and two similar side sections with or without end tabs which fold down over the 90 hinged end of the container. This blank is creased along its center line from end to end and may or may not be provided with reinforcing strips, stiffeners and/or a protective coating as 95 described in the said applications.

Before applying the bellows, the two side sections 1 and 2 are hinged together along the edges 3 with a non-dumping manifold 15 fastened into section 1, if a manifold and horizontal discharge port 7 are to be provided. Ports 7 and 9, and 10 100 if provided, are punched before hinging the two sections together. The manifold 15 may be of any suitable type, such as one of the types described in my pending applications, or the improved type described hereinbelow, and it communicates with the discharge port 7, as shown in Fig. 4.

While the non-dumping manifold may be omitted from containers intended to operate exclusively by discharging dusts upward through the port 9, it is an essential feature of the combination or general utility dusting carton which is the preferred embodiment of my invention. The function of the manifold is to prevent dumping or direct discharge through the port 7 of the insecticide, fungicide, or other pulverulent material with which the carton is filled, especially when dusting in a downward direction.

Generally speaking, the manifold which I prefer to employ consists of an outer casing which 120 is usually rectangular and of substantially the same length and depth as the side section of the container with which it is to be employed, the space within the casing being divided into two substantially parallel passages by means of a 125 middle lamella. One of these passages communicates with the discharge port 7 and the other passage communicates with the interior of the container through perforations or other openings in the manifold casing.

These two passages are connected by means of a port or opening through the lamella. The lamella may be flat throughout its length or curved at the end adjacent the discharge port 7 to meet the side of the casing, or curved at both 135 ends, and the opening through the lamella may be at the end opposite from the discharge port or at an intermediate point. Suitable manifolds of several types embodying various combinations of the above-mentioned and other features are 140 described in my pending applications Nos. 498,023 and 572,918.

While I may use any of the previously described manifolds in my present container, one of the features of the present invention is an improved 145 manifold which is adapted to use with this or other dispensing containers. This manifold 15 is rectangular, as shown in Figs. 4 and 7, and its middle lamella 18 is flat and parallel with the top and bottom of the casing.

The manifold is conveniently folded from a substantially rectangular blank shown in Fig. 5. This blank is divided into seven parallel sections designated as 17, 18, 19, 20, 21, 22 and 23, as shown. The second section from one end of the blank (section 18 in the drawings) forms the lamella of the finished manifold, and a portion of this section is cut out or omitted to form the connecting passage. One, or preferably two, of the sections at the other end of the blank (sections 22 and 23) are provided with perforations 25, and one of these sections, preferably section 22, is provided with one or more perforations 27 at the other end.

To form a manifold from this blank, the adjacent sections are folded at right angles, always in the same direction, starting with sections 17 and 18, as shown in Figs. 5, 6 and 7. Adjoining sections in the completed manifold, such as sections 17 and 21 and/or sections 19 and 23, may be fastened together in any suitable manner, as by gluing, stapling, or the like.

This manifold differs chiefly from one type of manifold described in my application Serial No. 572,918 in that the perforations 25 are fewer in number and are preferably confined to the front third of the manifold casing, that is, to the third adjacent discharge port 7 in the completed container, and in the provision of one or a few perforations 27 near the rear extremity of the casing. The perforation 27 is preferably of the same size or slightly larger than the perforations 25.

These improvements overcome the difficulties which have sometimes been encountered with previously described manifolds into which too much dust sometimes entered when dusting upward with a full package and not enough dust when the package was more than half empty.

The area of the opening through the middle lamella 18 and the total cross-sectional area of the perforations 25 and 27 should not be less than the area of the discharge port 7 and may be considerably greater. Each of the perforations 25 and 27 should be small enough to prevent the passage of large lumps of material therethrough, however.

The completed manifold 15 is inserted in side section 1 with one passage covering the discharge port 7, as shown in Fig. 4, and this manifold is fastened in place with glue or the like. Port 9 is punched in section 2, and sections 1 and 2 are hinged together along the edges 3, as previously stated. The sections are then partially closed together by rotation about the hinged edge.

The bellows blank prepared as described hereinabove is fastened to the partially opened side sections 1 and 2, preferably with quick-drying glue. When the glue sets sufficiently, the side sections and end section of the bellows are pushed in along the center line, giving the bellows the form shown in Figs. 3 and 1. This bellows is simple and strong, especially when provided with reinforcing strips and/or stiffening. It has a single inwardly extending fold on each side and in the preferred embodiment, the side folds are unbroken, giving the bellows maximum strength and durability.

Before filling, the two sides of the container are brought together in the position shown in Fig. 2. They may then be sealed in this position by means of an adhesive strip of paper or the like, with or without a rip cord, as shown and previously described, or the container may be filled before sealing. The discharge port 7, when in-

cluded, is closed with frangible or removable closing means, such as a cork or stopper, a movable metal disc, or a perforated seal of paper, cardboard, or the like.

The port 9 may also be closed in a similar manner before filling the container if a separate filling hole 10 is provided. If hole 10 is omitted, port 9 serves as a filling hole and is left open until the container is filled with insecticide, sulphur, dusting powder, or other pulverulent material, after which it is closed with a cork, seal, metal disc, or other suitable means.

The filled container may then be wrapped in a decorated wrapper bearing instructions or the like, which wrapper may serve as a seal to hold the container closed and the rip cord (if used) in place, or the two side sections may have been previously wrapped or otherwise decorated. An attractive, compact container is thus produced ready for shipment or sale.

When the container is to be used, the rip cord is pulled or the bellows is otherwise released and one of the discharge ports 7 or 9 is opened by removing the stopper therefrom. The two side sections are held in the user's two hands with the discharge port 7 away from the user in the upper left-hand corner, and the port 9 upward. By alternately opening and closing the bellows, a cloud of dust is expelled through the opened discharge port.

It will be obvious to those skilled in the art that certain modifications can be made in the several parts of my dispensing container and the several steps in its manufacture, in addition to those described by way of example hereinabove, without departing from the spirit of my invention, and it is my intention to cover in the claims such modifications as are included within the scope thereof.

I claim as my invention:

1. A dust-dispensing container comprising a closed receptacle including two side sections relatively movable about a hinge connecting the ends thereof, one of the side sections being provided with a non-dumping manifold and a discharge port in the hinged end thereof which communicates indirectly with the interior of the container through said manifold, and the other side section being provided with a discharge port in a side perpendicular to the hinged end thereof, whereby the contents of the container may be dispensed in an upward direction through the latter of said discharge ports while the container is held in a substantially horizontal position.

2. A dust-dispensing container comprising two relatively movable rectangular side sections of substantially equal size, said sections being connected by a hinge at one end and by a bellows at the other end and sides, said bellows having a single inwardly extending fold on each side, a discharge port in one of the side sections in a side thereof adjacent the bellows and perpendicular to the hinged end, a second discharge port in the hinged end of the other side section, and a non-dumping manifold establishing indirect communication between the second port and the interior of the container, whereby the contents of the container may be dispensed in an upward direction through the former of said discharge ports while the container is held in a substantially horizontal position.

3. A non-dumping manifold for dust-dispensing containers, comprising a rectangular casing and a middle lamella dividing the casing into parallel passages, the lamella being provided

80

with an opening by means of which communication between the passages is established, a plurality of perforations being provided through a wall of the casing on one side of the lamella, said 5 perforations being confined to substantially a third of the length of the casing adjacent one end thereof, and a perforation through one of the perforated casing walls adjacent the other end thereof, whereby to insure the supply of material to the manifold as the contents of the container become depleted.

4. A non-dumping manifold for dust-dispensing containers comprising a casing open at the ends and a middle lamella dividing the casing 15 into parallel passages of substantially equal cross-sectional area, the lamella being flat, parallel with at least one side of the casing, and shorter than the casing, whereby an opening is provided at one end of the lamella by means of 20 which communication between the passages is established, a plurality of perforations being provided through two walls of the casing on one side of the lamella, said perforations being confined to substantially a third of the length of the casing adjacent the end thereof which is farthest removed from the opening in the lamella, and a perforation near the other end of a casing wall 25 perforated in the manner aforesaid, whereby to insure the supply of material to the manifold as the contents of the container become depleted.

5. In a dust-dispensing container, the combination of a rectangular side section forming part of the body of said container, a port in the end of the said side section, and a non-dumping manifold providing indirect communication between the port and the body of the container, the said

manifold comprising a casing substantially equal in length to the interior of the container and divided into two parallel passages by a lamella through which an opening is provided at the end farthest from the port to connect the two passages, one of which communicates with the port and the other of which communicates with the interior of the container through perforations in the casing, the said perforations being arranged along substantially a third of the length of the casing adjacent the end thereof nearest the port, and a separate perforation provided near the other end of the casing to insure the supply of dust to the manifold as the contents of the container become depleted.

6. A dispensing container for pulverulent material, comprising two rectangular side sections of substantially equal size connected by a hinge at one end and a bellows with a single inwardly extending fold at the sides and the other end, a non-dumping manifold disposed in one of said side sections, a dispensing port in the hinged end of one side section of the container communicating with the interior of the container through said manifold, a second dispensing port in a side 100 of the other side section adjacent the bellows and near the hinged end of the container for dispensing material in a direction at right angles to the direction of material dispensed through said first mentioned port, said dispensing ports being of 105 substantially equal size and adapted to receive removable closing means, a rip-cord placed along the dividing line between the two side sections, and a frangible seal holding the side sections together and the rip-cord in place.
